UNITED STATES PATENT OFFICE.

WILLIAM LEE PILKINGTON, OF ST. HELENS, COUNTY OF LANCASTER, ENGLAND, ASSIGNOR TO PILKINGTON BROTHERS, OF SAME PLACE.

DESIGN FOR GLASS ORNAMENTATION.

SPECIFICATION forming part of Design No. 19,643, dated February 11, 1890.

Application filed December 7, 1889. Serial No. 332,969. Term of patent 14 years. Registered in England April 24, 1889, No. 124,118.

To all whom it may concern:

Be it known that I, WILLIAM LEE PILKINGTON, of St. Helens, county of Lancaster, Kingdom of Great Britain, a subject of the Queen of Great Britain, have invented and produced a new and original Design for an Ornamentation of Glass, of which the following is a specification, reference being had to the accompanying drawings, forming part thereof.

- 10 Figure 1 is a plan view of a plate of glass showing my design, and Fig. 2 is an edge view of the same, these two views being deemed necessary to fully illustrate my design.

The leading feature of my design consists 15 in a raised surface composed of the outlines of two substantially parallel vines, each comprising an irregularly-longitudinal stem or stalk with a group of leaves and tendrils, and a group of leaves and a flower blossom and 20 buds on each stem or stalk, and with the first-named group on each stem or stalk located opposite to the last-named group on the other stem or stalk, and with the flower-blossom in the group containing it on each stem or stalk 25 inclined toward the opposite leaf group on the other stem.

A and B are two substantially parallel vines, of which a and b are respectively the irregularly longitudinal stems or stalks. C and C' 30 are groups consisting of leaves c and tendrils c' on each stem or stalk, respectively. D and D' are groups consisting of leaves d, a flower-blossom d', and buds d² on each stem or stalk, respectively. The groups C and C' are located 35 on their stems or stalks, respectively, opposite

to the groups D and D' on the other stem or stalk, and the flower-blossom d' in the groups D and D' is inclined toward the group C or C' to which it is opposite on the respective vines. These said vines A B, with their respective stems a b, having, respectively, the leaf groups C C' and the described groups D D' located relatively to each other on the respective vines, as described, extend over the face of a plate of glass E as a raised surface 40 45 thereon.

I do not claim, broadly, herein a vine as an ornamentation for glass, as I am aware that vines have heretofore been employed for this purpose; but

50 What I claim is—

The design for an ornamentation of glass herein shown and described, comprising the outlines of two vines A B, each consisting, respectively, of an irregularly longitudinal stem 55 or stalk a b, with a group C C' of leaves and tendrils and a group D D' of leaves, a flower-blossom, and buds on each stem or stalk, respectively, and with the said groups C C' on the respective vines opposite the groups 60 D D' on the other vine, and with the flower-blossom in the groups D D' on the respective vines inclined toward the opposite groups C C', respectively, on the other vine, as set forth.

WM. LEE PILKINGTON.
